UNITED STATES PATENT OFFICE

2,518,643

TWO-PIECE BUTTON

John W. Sewell, St. Louis, Mo.

Application July 22, 1947, Serial No. 762,639

1 Claim. (Cl. 24—90)

1

This invention relates to improvements in metal buttons, and contemplates a construction in which the button is formed in two pieces, one providing a body providing a rolled rim and a central cupped portion, and the other providing a cap adapted to fit snugly in the cupped portion of the body.

It is among the objects of the invention to provide a button of the type described which is simple in construction and which may be manufactured at a relatively low cost.

Further objects of the invention reside in the provision of a button of the type described which is of rugged, durable construction, which is neat in appearance, and which presents only smooth surfaces at the thread openings, to the end that the thread securing the same to the garment will not be frayed or cut.

The invention, as will hereinafter fully appear, is applicable to two-hole and four-hole types, in which the holes extend transversely through the button, as well as to "shank" type buttons in which one or more passages extend through the rear face of the button, the front face being free from openings.

The foregoing and other objects and features of the invention will be made fully apparent to those skilled in the art from a consideration of the following detailed description taken in conjunction with the accompanying drawings, in which:

Figure 1 is an elevational view showing the front face of a four-hole button constructed in accordance with the invention.

Figure 2 shows a section taken on the line 2—2 of Figure 1.

Figure 3 is a fragmentary section showing the application of the invention to the body of a button of the type having a thread passage through the rear face only of the button.

Figure 4 is an elevational view showing the rear face of the fragment shown in Figure 3.

Figure 5 is a view similar to Figure 3, but with the closing cap for the central pocket of the body portion in position.

In the drawings, reference numeral 10 indicates generally the body portion of the button, which body is formed of a single disc of sheet metal, the periphery of which has been rolled into an oval rim 11. The rolled rim 11 is completely closed, being formed with a slight overlap, as will be seen in Figure 2, and from the rim 11 a web portion 12 formed of a single thickness of the sheet metal tapers slightly in the direction of the rear face of the button to the

central pocket 13. The pocket 13 is formed by extruding the metal of the disc rearwardly and has a smooth cylindrical interior wall and a flat internally-projecting annular flange 14, from the inner edge of which the metal is further extruded rearwardly, as indicated at 15, so that the bottom of the pocket lies rearwardly of the flange 14. From the rear side of the button the bottom of the pocket is pierced inwardly to form a number of thread holes 16. In this instance, four holes 16 are shown. However, it will be understood that a two-hole button may be formed in the same manner. The metal around the thread holes 16 is extruded inwardly toward the front of the button, the interior wall of this extruded portion being smooth and round and extending to the plane of the front surface of the annular flange 14.

The central cupped portion of the body 10 of the button is closed by a cap indicated generally at 17. The cap is formed of a metal disc having its central portion pressed outwardly, as indicated at 18, leaving a flat peripheral flange 19. The diameter of the cap so formed is such as to provide a press fit between the cap and the cylindrical wall portion of the pocket 13 of the body 10. The outwardly-pressed portion 18 of the cap is pierced inwardly from the front side thereof to form a number of thread holes 20. The number and spacing of the holes 20 correspond to the number and spacing of the thread holes 16 formed in the central pocket of the body member 10. The metal around the thread holes 20 is extruded inwardly toward the rear of the button, the interior wall of this extruded portion being smooth and round, corresponding to the thread holes 16, and these extruded portions extend to the plane of the rear face of the annular flange 19.

The two pieces comprising the body 10 and cap 17, formed in the manner described, may be easily assembled by pressing the cap into the cylindrical portion 13 of the central pocket of the body 10 with the thread holes 16 and 20 in alignment. When the two pieces are so pressed together with the rear face of the flange 19 on the front face of the flange 14, the extruded walls of the thread holes 16 and 20 are in contact at the interior ends thereof forming smooth, continuous passages through the button. The press fit may be relied upon to hold the two pieces together, or the parts may be swaged and corrugated, the corrugations extending radially of the button in the flange portions 14 and 19. The construction described in the foregoing

may be slightly modified, as illustrated in Figures 3, 4, and 5, to provide a button of the type having a thread hole or passage extending through the rear face of the button, and having no openings through the front face. Such buttons are sometimes called shank buttons, and will be so referred to herein.

In these figures, a portion of the web of the button is indicated at 22, and it will be understood that this portion corresponds to the web 12 of the form previously described. In the modified form, the button is also provided with a central pocket having a smooth, cylindrical, interior wall portion terminating in a flat, internally-projecting annular flange 24. From the inner edge of the flange 24 the metal is further extruded rearwardly, as indicated at 25. The extruded portion 25 extends substantially further than the extruded portion 15 of the form previously described.

The rounded sides of the extruded or outwardly-pressed portion 25 are pierced on diametrically opposite sides thereof with punches designed to split the metal at the central point of the punch, forcing the metal inwardly, as indicated at 26. Preferably, the punches will be of a generally rectangular cross-section, and the two openings so formed jointly provide a thread passage extending through the button in a direction substantially parallel with the central plane thereof.

The central pocket of the button is closed with a cap indicated generally at 27. This cap corresponds to the cap 17 of the form previously described, having a portion 28 pressed outwardly from a peripheral flange 29. However, this portion 28 has no perforations corresponding to the perforations 20 of Figures 1 and 2, leaving the front face of the button imperforate. In this form also the cap 27 makes a press fit with the cylindrical wall portion of the pocket 23.

While there have been herein described certain preferred embodiments of the invention, other embodiments thereof, within the scope of the appended claim, will be obvious to those skilled in

the art from a consideration of the forms shown and the teachings hereof.

Having thus described the invention, I claim:

A button comprising a sheet metal disk deformed at its center to provide a rearwardly offset circular cup portion having an annular sidewall and a plane bottom plate, said bottom plate being connected to the rearward edge of said annular sidewall, said bottom plate being formed with spaced thread holes and the material of the bottom plate between and surrounding the thread holes being rearwardly displaced with respect to the plane of said bottom plate and curved forwardly so as to provide rounded margins around the thread holes, a plane circular front plate secured in said cup and engaging the forward side of said bottom plate, said front plate being formed with thread holes registering with the thread holes of the cup bottom plate, the material of said front plate between and surrounding its thread holes being curved forwardly with respect to the plane of said front plate to provide rounded margins around the thread holes, the rounded margins of the cup bottom plate and of the front plate conjoining to provide continuous convexly rounded surfaces.
